**C. A. NELSON,
CARTRIDGE GUIDE FOR FIREARMS.
APPLICATION FILED AUG. 22, 1916.**

1,256,924.

Patented Feb. 19, 1918.

UNITED STATES PATENT OFFICE.

CHARLES A. NELSON, OF UTICA, NEW YORK, ASSIGNOR TO SAVAGE ARMS CORPORATION,
A CORPORATION OF DELAWARE.

CARTRIDGE-GUIDE FOR FIREARMS.

1,256,924.

Specification of Letters Patent. Patented Feb. 19, 1918.

Application filed August 22, 1916. Serial No. 116,230.

To all whom it may concern:

Be it known that I, CHARLES A. NELSON, a United States citizen, residing in Utica, New York, have invented the following-described Improvement in Cartridge-Guides for Firearms.

This invention is an improvement in cartridge feeding mechanism for fire-arms and more particularly that type of fire-arm in which the cartridges are advanced sidewise from a laterally moving cartridge supply or carrier into the path of mechanism operating to push them endwise into the barrel, such for example, as the well known Savage-Lewis machine gun in which the cartridge magazine rotates step by step over the breech mechanism and the cartridges are carried into contact with a yielding cam mechanism forcing them successively downward into the path of the breech bolt, by which they are thrust endwise into the chamber when the bolt moves forwardly to closed position.

In McLean Patents Nos. 1,042,363 and 1,042,135 spring-pressed plungers are employed to depress the cartridges. The construction involves an endwise bodily movement of the entire plunger member on each operation and the dimensions necessary for such plungers to operate effectively are of such magnitude that the speed of movement is therefore limited and the vibration of its very considerable mass transversely of the axis of the gun interferes with aiming. Furthermore, it is only with difficulty that the plunger member can be removed in case of breakage or wear. Attempts to overcome these and other objections have involved the substitution of an inclined leaf spring yielding substantially upwardly as the cartridge is forced therebeneath and such a spring is highly satisfactory so long as it retains its original form and character but the complexity of the strains to which it is subject brings about an early deterioration and eventual fracture, merely as the result of continued normal operation and this is not avoided by exercising the greatest care in the manufacture and tempering of the spring.

The present invention consists in a cartridge directing member possessing the advantage of small mass and low inertia, which is the principal merit of the described spring, together with a maximum resistance to wear and constant vibration to enable it

to continue its proper function for an indefinite period thereby affording all of the advantages of the spring without its attendant weakness, and this object is accomplished by means of a swinging cam-faced finger which is directly encountered by the sidewise-moving cartridge and adequately supported to sustain the thrust therefrom and also by means of a spring which acts on the said member to press it and the cartridge riding under it, downwardly into the breech casing, the spring-yielding functions being thus entirely separated from the wear and thrust-resisting functions of the mechanism. The spring itself, which may be an ordinary helical spring, is protected in this relation, from the sidewise thrust of the cartridge and is free from localized distortion tending to crystallize it. It acts only in the direction in which it is desired to move the cartridge. The cam-faced finger swings vertically and by virtue of its pivotal mounting is properly and satisfactorily made of very light weight and of material, best suited to resist the vibration and wear to which it is subject. It is readily designed moreover so that it may be easily and quickly inserted and removed and without the use of special tools when necessary.

Although my invention is particularly applicable to the Savage-Lewis machine gun above referred to, it will be evident that it may, by obvious change in form be applied to other types of guns where similar objections are to be overcome, or where it may be employed with advantage.

In the accompanying drawings, I have illustrated a preferred embodiment for the type of gun referred to, the parts of the latter not directly involved being omitted for the sake of clearness.

Figure 1 is a top plan view with magazine broken away;

Fig. 2 is an enlarged scale plan of the finger in its support;

Fig. 3 is a transverse section of the receiver or frame of the gun at the location of the cartridge directing finger, showing also the magazine and some cartridges;

Fig. 4 is a side elevation of the cam-faced finger in its holder;

Fig. 5 is an end view of the holder;

Fig. 6 is an end view of the finger;

Fig. 7 is a bottom plan thereof; and

Fig. 8 illustrates the removable locking

pivot of the finger with relation to the holder.

In the type of gun illustrated, the cylindrical magazine indicated at 1 is mounted 5 on an upstanding post 2 shown in dotted lines (Fig. 1) and will be understood to comprise the usual central non-rotatable part 3 having a helical peripheral groove to conduct the bullet ends of the cartridges 10 and the usual drum or shell part 4 for carrying the base ends of the cartridges whereby, on the rotation of the shell the cartridges are advanced in a circular or helical direction toward the end of the groove and exit 15 of the magazine. Pivottally mounted upon the post 2 is a cartridge feeding arm 5, the rear part 6 of which is curved and provided with a cam slot engaged by an upstanding projection 7 on a part of the reciprocating 20 breech mechanism. The action of the latter swings the arm back and forth on the post 2 as a center and in its movement in one direction (upward in Fig. 1) its dog 8 engages the rotatable shell part 4 of the magazine to advance it one step in a clockwise direction. 25

The feeding arm 5 has a cartridge slot 9 directly beneath the magazine and adapted to coincide with the exit point thereof as it 30 swings to the position indicated in Fig. 1. Each cartridge, advancing downwardly from the magazine exit into this slot is carried laterally by it, sliding on the surface 10 to a position directly above the axis of 35 the barrel where it rests in a slot 11 in the upper part of the breech bolt chamber 12, protruding more or less into said chamber as shown at 13 (Fig. 3.) In this position the head of the cartridge is engaged by the advancing breech bolt and pushed forwardly 40 to a wider part of the entrance 11, whereby it is caused to drop directly in front of the bolt for entry into the barrel chamber. The foregoing construction and mode of operation 45 is well known to the art.

The rear end of the cartridge feeding arm 5 is normally covered by a plate 14, shown broken away for convenience, in Figs. 1 and 2 and an extension 14^a of this plate 50 forms the support for the finger or cartridge guide to which my invention pertains, although other supports could be found for said guide if necessary. By means of the extension 14^a it is held directly over and opposed to the entrance 11 to the bolt chamber. 55

The finger holder 15, shaped substantially as shown in Figs. 4 and 5 is set in this extension 14^a by means of a T-head on the former and an undercut groove in the latter and is thereby held with its open side downward and directly over the rear parts of the cartridges which, as above stated, move sidewise beneath it. The holder is desirably curved concentrically to the magazine pivot 2 and has a roof part and two side

walls with inturned edges. The cam-faced finger 16 is contained within the holder and sustained therein by the side walls and by its pivot or retaining pin 17, the latter being inserted through the side wall. This retaining pin is provided with a handle part marked 17^a, normally disposed on the forward side of the holder, and the end of the handle part 17^a is bent at an angle to the main part 17 so that it may be turned or snapped into a correspondingly inclined notch 17^b in the holder side wall. The pin is thereby locked in place—by virtue of the acute inclination of the notch 17^b with reference to the general direction of withdrawal of the pin 17 from the holder—but it can be instantly removed by springing the bent over end out of the notch as will be evident. 75

The free end of the finger 16 is upturned and provided with a rounded nose 16^a at the junction of the upturned end and the body part, this formation providing a proper directing or cam face which the cartridges may encounter. Its oscillating free end is urged downwardly by the helical spring 18 90 which seats against a boss on the roof part of the holder and in a socket or recess on the upper side of the finger. As apparent in Fig. 3 the spring 18 urges the finger downwardly and thereby depresses the cartridge (13) into the entrance to the bolt chamber giving it its direction while the bolt advances it into the barrel. While the pin 17 constitutes a pivot for the finger it is desirably made with an easy fit in the hub part 95 thereof so that it does not receive the end thrust imparted to the finger from the cartridges. Such thrust is imparted lengthwise through the finger to its tail piece 16^b which finds a very solid abutment against the end wall 15^a of the holder, as shown in Fig. 4, and without impeding its swinging movement. The lateral thrust on the cam finger, such as results from the forward movement 100 of the cartridge while engaged with the finger, is resisted by the forward side wall of the holder 15 and with this disposition of endwise and lateral abutment it will be plain that the finger itself may be made of extremely light mass as shown in the drawings. 105 The action of the spring 18 is merely one of compression and expansion and is always in the direction of its own axis so that it is therefore capable of a practically infinite number of operations without deterioration. Fig. 3 illustrates the finger in its uppermost position, with the thrust taken on the abutment face 15^a and with the spring compressed and exerting its pressure through the finger upon the cartridge, the latter being shown in the position it holds 115 as the breech mechanism begins its closing movement.

It will be understood that the principle of this invention as exemplified by the above 120

described parts and as herein fully explained, may also be utilized in other forms than that illustrated and that various modifications and changes in the proportions and relative arrangement of the parts may be resorted to without departing from this invention.

Claims:

1. In a fire-arm, the combination of a reciprocating breech bolt, a receiver having an opening in the upper side through which cartridges may be fed, means for delivering cartridges transversely of the receiver to its opening, and a spring-pressed finger pivoted to swing upwardly out of the path of the cartridges as they approach said opening and serving to guide them during their movement into said opening.
2. In a fire-arm of the kind described, the combination of a breech-bolt chamber, a magazine and means for transferring cartridges laterally therefrom to the entrance to said chamber, of a cartridge guiding and depressing member associated with said entrance, and comprising a rigid finger held against movement in the direction of the thrust of the moving cartridge and a spring acting on said finger and permitting movement of the latter in a direction at an angle to the direction of thrust.
3. In a fire-arm the combination with a breech-bolt chamber, a magazine and automatic means for transferring cartridges from the latter to the entrance of said chamber, of a cartridge guiding member opposed to said entrance and comprising a holder, a swinging cam-faced finger confined therein and sustained thereby against endwise and lateral thrust of the cartridges and a spring interposed between the holder and finger and free from the thrust strains on said parts.
4. In a fire-arm, the combination of a receiver having a cartridge entrance opening in the upper side thereof, means for moving cartridges transversely of said receiver to said opening, and a finger pivoted at the far side of said opening and movable upwardly by the engagement of a cartridge beneath the free end thereof to permit the cartridge to enter said opening, and means for urging the finger downwardly.
5. In a fire-arm, the combination of a receiver having a cartridge entrance opening in the upper side thereof, means for moving cartridges transversely of the receiver to its opening, and a spring-pressed cam-faced finger pivoted at the far side of the opening and movable upwardly by the engagement of a cartridge beneath the free end thereof to permit the cartridge to enter said opening.
6. In a fire-arm, the combination of a

cartridge feeding mechanism, a movable magazine, a cover plate for said mechanism, having a forward extension beneath said magazine and a cartridge guiding finger pivotally supported at the end of said extension and extending in the general direction of movement of said magazine, and a holder for said finger.

7. In a fire-arm, a cartridge directing member mounted to swing on a loose pivot, a fixed abutment to sustain the thrust on said member during the swinging movement, and a spring pressing the said member toward the path of the cartridges.

8. A fire-arm having a cartridge guide in the path of movement of the cartridges, one end of said guide having an endwise abutment and the other being free to oscillate and a spring engaging the said free end to press the same against the cartridges.

9. A fire-arm having a swinging and spring-pressed finger in the path of movement of the cartridges, and a retaining pin therefor, said pin having an extension at one end thereof, at an acute angle to the general direction of the withdrawal of said pin and rotatable about the latter as an axis into and out of locking engagement with a co-acting part to prevent or permit endwise movement of said pin.

10. In a fire-arm, the combination of a holder including a top wall, side walls and inwardly directed flanges at the free edges of the latter, a finger pivotally mounted between said side walls and movable between said top wall and said flanges and having an upturned end forming a cam-face in the path of movement of the cartridges, and a spring intermediate of said top wall and said member.

11. In an automatic gun of the kind described, a magazine rotating over the entrance to the breech-bolt chamber, an open bottomed holder held between the magazine and chamber, a cartridge directing finger carried by said holder and a spring within the holder urging the finger downwardly toward the said chamber entrance.

12. In an automatic gun of the kind described, a magazine rotating over the entrance to the breech-bolt chamber, means for transferring cartridges laterally into said entrance, a light finger opposed to said entrance and mounted to receive the thrust from the cartridges in the direction of its own longitudinal axis, and a spring separate from said finger acting thereon transversely to said axis and adapted to depress cartridges into the said entrance.

In testimony whereof, I have signed this specification.

CHARLES A. NELSON.
